J. E. MARSHALL,
INCLINOMETER,
APPLICATION FILED AUG. 29, 1917.

1,271,049.

Patented July 2, 1918.

UNITED STATES PATENT OFFICE.

JAMES E. MARSHALL, OF CANEY, KANSAS.

INCLINOMETER.

1,271,049.

Specification of Letters Patent. Patented July 2, 1918.

Application filed August 29, 1917. Serial No. 188,358.

To all whom it may concern:

Be it known that I, JAMES E. MARSHALL, a citizen of the United States, residing at Caney, in the county of Montgomery and State of Kansas, have invented certain new and useful Improvements in Inclinometers, of which the following is a specification.

This invention has relation to levels for aeroplanes, airships or the like, and has for 10 an object to provide a device for the purpose of indicating the extent of inclination of the machine either longitudinally or laterally relative to the surface of the ground.

Another object of the invention is to provide 15 a device of this character embodying one or more indicating elements, pivotally mounted and weighted so that one or the other may maintain at all times a vertical position irrespective of the inclination of 20 the machine, and a stationary graduated element located near said pointers to indicate the nature and extent of the inclination of the machine.

In addition to the foregoing my invention 25 comprehends improvements in the details of construction and arrangement of the parts to be hereinafter more fully described, and particularly set forth in the appended claim.

30 In the accompanying drawings in which similar and corresponding parts are designated by the same characters of reference throughout the several views in which they appear:

35 Figure 1, is a view in front elevation of the preferred form of my level indicator.

Fig. 2, is a vertical section taken on the line 2—2 of the preceding figure.

40 Fig. 3, is a vertical section taken on the line 3—3 thereof.

With reference to the drawings, 10 and 45 11 indicate drums disposed in a vertical plane and at relative right angles. Both drums are supported upon a frame which is indicated at 12. The frame 12 carries at one end a pair of upstanding arms 13, apertured at their upper ends to receive trunnions 14 which projects from the periphery of the drum 10 to pivotally support the same 50 between the arms. In order that the drum 10 may be retained at all times in an upright position the trunnions 14 are located slightly above a horizontal line taken diametrically through the drum.

55 The other drum 11 is pivotally mounted upon upstanding arms 15 which are mount-

ed upon an extension 16 of the frame 12 whereby to dispose the drums 10 and 11 in the manner stated above. The peripheries of the drums 10 and 11 are graduated as indicated in the figures and the graduations extend from a point marked zero at the upper edge of both drums, down both sides to a point marked 180°, the graduations zero and 180 being both located in a vertical 60 65 diametrical plane.

Mounted centrally upon the drum 10 is a pointer 17 for pivotal movement, having the lower end weighted as at 18, and the upper end bent as at 19 to extend over the periphery of the drum.

A pivot 20 is supported upon the drum 11 centrally thereof whereby to support for rotation a pointer 21, having its lower end weighted and its upper end bent over the 70 upper edge of the drum 11 in the manner of the pointer 17.

It will be noted that the drums 10 and 11 are mounted in a manner to permit oscillatory movement thereof in directions at 80 right angles to each other.

The frame 12 is provided with an integrally formed depending bolt 22 which is adapted to extend through an elongated opening or slot 23 of one arm 24 of an angle 85 bracket, the other arm 25 being apertured to permit the passage of bolts therethrough to secure the angle brackets to some stationary portion of the aeroplane. A thumb nut 26 applied to the bolt 22 serves to secure 90 the frame in place subsequent to adjustment longitudinally of the bracket.

In use, the device is mounted in an aeroplane in such a way as to dispose the drum 10 transversely of the machine and the drum 11 longitudinally thereof. It will be apparent that when in flight the forward or rearward inclination of the machine will be indicated by the pointer 12 which, being weighted to maintain a vertical position will indicate upon the graduations of the drum 11 the extent of the inclination whether the drum is in a forward or rearward direction. Conversely, should the machine be inclined laterally to one side or the other this fact 100 105 will be indicated by the pointer 17 upon the graduations of the drum 10 since an inclination of the machine in a forward direction, either downwardly or upwardly is frequently accompanied by an inclination of 110 the machine laterally. Also the drum 10 is pivoted to permit free movement of the

pointer 17 when the machine is inclined in this manner to indicate the extent of both inclinations of the machine. An illuminant of any character desired may be positioned above the device so as to illuminate the dials when traveling at night.

Having thus described my invention what I claim as new and desire to secure by Letters Patent is:—

- 10 An inclinometer including an angular bracket having a slot in one arm, a threaded member extending therethrough, a wing nut applied to said threaded member to secure the same in place, a plate mounted on said threaded member and having at each end a pair of upstanding horizontally spaced arms,
- 15

said pairs of arms being located at relative right angles, a drum pivotally mounted within the extremities of each pair of arms for oscillation in a vertical plane, said drums bearing graduations upon one side face, and their peripheries, and a weighted pointer pivotally mounted upon the center of each drum and having one end bent at right angles to extend across the periphery of the drum.

In testimony whereof I affix my signature in presence of two witnesses.

JAMES E. MARSHALL.
